United States Patent Office

Des. 176,938
Patented Feb. 14, 1956

176,938

SOFA

Forest Wilson, Chicago, Ill., assignor to Stradford Furniture Corporation, Chicago, Ill., a corporation of Delaware

Application February 25, 1954, Serial No. 29,211

Term of patent 7 years

(Cl. D15—11)

FIG. 1

FIG. 2

FIG. 4

I claim:

The ornamental design for a sofa, as shown.
